UNITED STATES PATENT OFFICE.

WILLIAM E. WALSH, OF MORRIS, ILLINOIS.

WINDOW-TENT.

No. 873,971.

Specification of Letters Patent.

Patented Dec. 17, 1907.

Application filed February 5, 1907. Serial No. 365,917.

To all whom it may concern:

Be it known that I, WILLIAM E. WALSH, a citizen of the United States, residing at Morris, in the county of Grundy and State of Illinois, have invented certain new and useful Improvements in Window-Tents, of which the following is a specification.

The present invention relates to window tents of the general style shown in Patent No. 840,976, of January 8, 1907, which have for their object to provide means for supplying fresh air to the lungs of persons afflicted with tuberculosis or diseases of a similar nature, or to any persons desiring the beneficial effects of fresh air supplied to the lungs during sleep and without the inconvenience of living in a tent or out-of-door structure.

The tent of the present invention is adapted to have the patient's head inserted into an opening in the tent box, leaving the body of the patient within the room and unexposed to the cold air from out of doors. The device as a whole is adapted to be inserted through a window and forms in effect a ventitating shaft leading from the exterior of the house to the interior of the room.

The present invention, moreover, relates to the construction of the frame-work which enables the interior or box portion of the tent to be swung to different angles with respect to the window to accommodate different conditions within the room. In some cases it is impossible to position the patient's bed directly alongside of the window, in which case it becomes necessary to swing the box to different angles with respect to the framework inserted and held within the window. The present invention provides means for permitting this swinging or hinging action of the box and thereby permits the tent to be used under conditions which would prevent the using of a tent not thus constructed.

In the drawings Figure 1 is a perspective view of the framework of the preferred form of tent, showing in dotted lines the position of the canvas cover; Fig. 2 a top or plan view of the same, showing the covering in position; Fig. 3 a top edge view of a modified style of framework in closed position; Fig. 4 a similar view showing one section of the frame moved to an angle with respect to the other; Fig. 5 a side elevation of a second modification of the frame work; Fig. 6 a top or plan view of the same, showing the cover; Fig. 7 a plan view of the bracket of Fig. 5; Fig. 8 an elevation of the bracket of Fig. 5; and Fig. 9 a sec-

tional view through the frame showing a method of regulating the curtain.

In the preferred form of construction illustrated in Figs. 1 and 2 the tent is provided with a frame work consisting of a rectangular fixed section 9 and a similar hinged section 10, each section being in the form of an open frame-work; and the fixed section 9 is provided with side rails 11, a top cross rail 12, and a bottom cross rail 13. The hinged section likewise comprises side rails 14, a top cross rail 15, and a bottom cross rail 16. The fixed and movable frame sections are connected together by means of lazy tongs 17, the forward end sections of which are provided with sleeves 18 which are slidably mounted on rods 19 extending from top to bottom of the fixed frame section near the side rails thereof. The rear sections of the lazy tongs are likewise provided with sleeves 20 slidably mounted upon rods 21 which extend from top to bottom of the movable or hinged frame section near the side rails thereof. This arrangement permits the movable or hinged frame section to be swung to any suitable angle with respect to the fixed frame section, or to be retracted in a plane parallel therewith.

The movable frame section has secured thereto a wire bracket 22 which comprises diagonally extending side portions 23, each having a loop 24, the rear ends of which side portions are connected by means of a cross rail 25. This wire bracket, in connection with the movable frame section, affords a support for the tent box 26 which is formed of canvas of similar material. The construction of the canvas box is particularly described in my Patent No. 840,976, and it is not deemed necessary to enter into a detailed description thereof. The space occupied by the lazy tongs, between the fixed and movable frame sections, is covered by a section of bellows-folded fabric 27 which permits of expansion in either direction.

The fixed frame section is provided with a forwardly extending hinged bracket 28 which serves as a support for a canopy 29, and the surplus window space is adapted to be closed by means of exterior side curtains 30 mounted upon an extensible frame-work 31 of the character shown in my patent above referred to. It is not deemed necessary to give a more detailed description of these features of the tent for the reason that they are in all respects similar to those described in my prior

patent, the present invention relating entirely to the method of connecting the sections of the frame-work.

In Figs. 3 and 4, in place of lazy tongs for connecting the fixed and movable sections of the frame-work, is shown a connection comprising hinge sections 32 and 33, the former of which is secured to the fixed section 9 and the latter of which is secured to the movable 10 or hinged section 10. The hinge sections are duplicated on each side of the frame, and the sections are hinged together by means of the pintle rods 34, either of which can be removed to permit the movable section of the 15 frame to be swung outwardly in the desired direction, as indicated in Fig. 4. In constructing the tent in the manner shown in Figs. 3 and 4, the remaining features of the tent are precisely similar to those hitherto 20 described.

In Figs. 5, 6, 7 and 8 is shown a second modification in which the movable rectangular frame section is dispensed with and the wire bracket is secured directly to the fixed 25 frame section, which, in this modification, is indicated by the numeral 35. The wire bracket comprises side rails 36 and a cross rail 37, which latter is formed separate from the side rails and is hinged thereto at its ends 30 to permit the parts to be swung to different angles. The forward ends of the side rails are entered into sockets 38, each socket being provided with a flat disk-shaped tongue 39 which co-operates with a similar tongue 40 35 outwardly extending from a clutch section 41. The disk-shaped tongues lie in facial contact with one another and are held together by means of a thumb screw 42 which permits the socket to be turned to different 40 angles of elevation with respect to the clutch section. The clutch section 41, which may be termed the movable clutch section, co-operates with a fixed clutch section 43 formed integrally with and outwardly projecting 45 from a plate 44 secured to the lower corner of the frame 35. This arrangement permits the side bars or arms of the bracket to be individually turned to different angles with respect to the fixed frame, and there- 50 after clamped by means of a thumb screw 45, which serves to clamp the two clutch sections together. The bracket 36 is covered by means of a covering 46 of suitable fabric which is sufficiently long to permit of consider- 55 able movement of the bracket without binding or stretching. The remaining features of the tent of Figs. 5, 6, 7, and 8 are similar to those hitherto described, and to the tent described in my patent previously 60 referred to.

Fig. 9 illustrates a curtain 47 which may be secured to the frame of either form of construction and is adapted to be raised and lowered by means of an endless cord 48 65 which passes through upper and lower eye-

lets 49, to which cord the curtain is attached. This permits the patient to regulate the admission of air to the box of the tent by raising or lowering the curtain either wholly or in part.

In using the tent of any of the forms of construction heretofore described, the fixed section of the frame is inserted into place within the window, and the extensible curtains are drawn out to fill the surplus space 75 within the window, after which the window is lowered to clamp the fixed section of the frame in place. The box portion of the tent can thereafter be adjusted to any desired angle or retracted to extend to any suitable 80 distance into the room to accommodate the conditions of use. In using the tent illustrated in Figs. 1 and 2 the lazy tongs can be extended on either side by merely pulling the box around in the desired direction and 85 without further manipulation. In the form of construction shown in Fig. 3, it will be necessary to remove one of the pintle rods in order to permit the box to be swung in the desired direction; and in the construction 90 of Figs. 5, 6, 7, and 8 adjustment of the clutch sections is necessary. All of the different forms of construction, however, permit the box to be swung from side to side in order to accommodate the conditions within 95 the room.

What I regard as new and desire to secure by Letters Patent is:

1. In a device of the class described, a frame adapted to be held within a window, a canopy portion outwardly projecting from the frame, and a box portion secured to the frame and adapted to be swung at different angles with respect thereto, substantially as described.

2. In a device of the class described, the combination of a fixed frame, a canopy portion outwardly projecting from the fixed frame, a supporting bracket adjustably mounted with respect to the fixed frame, and a box portion carried by the bracket and adapted to be swung at different angles with respect to the fixed frame, substantially as described.

3. In a device of the class described, the combination of a fixed frame and a movable frame, a canopy secured to the fixed frame, a box secured to the movable frame, and an adjustable connection between the two frames for permitting the box to be swung at different angles, and a flexible covering for the connection, substantially as described.

4. In a device of the class described, the combination of a frame adapted to be held within a window, a bracket connected with the frame and adjustable to different angles with respect thereto, and a box carried by the bracket, substantially as described.

5. In a device of the class described, the combination of a fixed frame, a movable

frame, a lazy tong connection between the two frames, a flexible covering between the two frames, and a box carried by the movable frame and adjustable to different angles 5 with respect to the fixed frame, substantially as described.

6. In a device of the class described, the combination of a fixed frame, a movable frame, a lazy tong connection between the 10 two frames, a flexible covering between the two frames, a box carried by the movable frame and adjustable to different angles with respect to the fixed frame, and a canopy secured to the fixed frame, substantially as de- 15 scribed.

7. In a device of the class described, the combination of a fixed frame, a canopy outwardly projecting therefrom, a movable frame, a bracket secured to the movable 20 frame, a box-shaped covering of fabric secured at its forward edges to the movable

frame and held distended by the bracket, lazy tong connections between the fixed and movable frames, and a bellows-folded covering between the two frames, substantially as 25 described.

8. In a device of the class described, the combination of a frame, a box-shaped covering secured at its forward edges to the frame, a bracket for supporting the covering, said 30 bracket comprising side arms and a connecting cross arm, and adjustable clutch connections between the forward ends of the side arms and the frame for permitting the box to be swung to different angles with respect to the frame, substantially as de- 35 scribed.
